(57) **CLAIM**

The ornamental design for a smoking cup, as shown and described.

DESCRIPTION

FIG. 1 is a top, front perspective view of the claimed design. FIG. 2 is a top, rear perspective view of the claimed design. FIG. 3 is a front elevational view of the claimed design. FIG. 4 is a rear elevational view of the claimed design. FIG. 5 is a top plan view of the claimed design. FIG. 6 is a bottom plan view of the claimed design. FIG. 7 is a left side elevational view of the claimed design; and, FIG. 8 is right side elevational view of the claimed design. The broken lines depict portions of the smoking cup and form no part of the claimed design.
